William Cole of Pitts, Massachusetts.

Pitter's Patent.

Dated January 23d 1833.

The Schedule referred to in these Pitts Patent, and making part of the same, containing a description in the words of the said William Cole himself, of his improvement in washing felt in a machine for making paper, called a "Felt Washer".

To all to whom these presents shall come: Be it known, that I, William Cole of the County of Berkshire in the Commonwealth of Massachusetts, have invented a new and useful improvement in washing felt in the machine for making paper, and that the following, and the annexed drawing, is a full and exact description of the construction and operation of the same, as invented or improved by me.

The annexed drawing represents that part of a machine for making paper by power or other power to which the said improvement belongs. C, the backer cyl. in which W, the web or sheet of paper is communicated over felt onto the cylinder T, called the "Pay boy," also between cylinder or press roller, marked P, P, then passes back to C, under roller 1, over roller 2, and under roller 3. And on its way from this last roller.

What I claim as new and as my own invention or discovery in the above described machine, and for the use of which, I ask an exclusive privilege, is a Felt Washer, which is constructed as follows, as per A, in the drawing, and as per B, in the separate drawing. It is a float wheel of four arms at right angles on each end of a shaft, of sufficient length for the width of the felt or web, and a float or bar framed or fastened on the end of each arm, as at 0, 0, 0, 0, in each of the former drawing. The floats or bars as b, b, b, b, in fig. B. This wheel to be placed under the felt or web in such a position, that the floats or bars shall strike or beat the felt underneath, in a contrary as the felt ascends to C, that is toward S. The power applied to motion this Felt Washer may be in various ways, and quicker or slower, one way by a cross band from wher it is, on the end of shaft P, to wher A, is on the end of shaft A, the Felt Washer.

But in order that the felt washer may do its part of work a thin or other tube, of small or large caliber, thickly perforated with small holes, must be placed at the opposite side of the felt, near where the floats of the pulp strike or beat the felt most strongly; and this tube must be forced into a hole that is made through the holes directly on the felt, which may be done by a hydraulic pump or otherwise, and stopped at pleasure; see Fig. 3; - a aqueduct, 3, stop cock 6, tube.

The only claim concerning this tube, the relative situations here placed in connection with the felt washer; yet it is an improvement in this respect, and may be considered as part of this invention. This improvement and invention may be used in a cylinder, trode, or any other machine mill and will be cheaper the felt as to supersede the necessity of removing the same until it is fully worn out, all which is considered a very great saving, and find a application to the art of paper making of which the inventor professes to be well acquainted.

Witnessed,

Ransom Gleiman
